CIGARETTE EXTINGUISHER

John B. Morton, Culver City, Calif.
(2137 Viking Ave., Anaheim, Calif. 92806)

Filed July 3, 1967, Ser. No. 7,699

Term of patent 14 years

(Cl. D85—2)

FIG. 1.

FIG. 3.

FIG. 4.

FIGURE 1 is a perspective view, taken from above, of a cigarette extinguisher showing my new design; FIG. 2 is a perspective view thereof, taken from below; FIG. 3 is a top plan view thereof; and FIG. 4 is a side elevational view thereof.

I claim:

The ornamental design for a cigarette extinguisher, substantially as shown.
